UNITED STATES PATENT OFFICE.

CHARLES F. YARDLEY, OF LARCHMONT, NEW YORK.

RAIL ANCHOR.

Application filed March 1, 1923. Serial No. 622,041.

To all whom it may concern:

Be it known that I, CHARLES F. YARDLEY, a citizen of the United States, residing at Larchmont, in the county of Westchester and State of New York, have invented certain new and useful Improvements in Rail Anchors, of which the following is a specification.

My invention relates to rail anchors.

10 It has for its principal object the provision of an anchor comprising a body portion and two jaws so arranged at opposite ends thereof that when the device is applied with the jaws in operative engagement with the opposite flanges of the rail base, with the body of the anchor in a position diagonal to the longitudinal axis of the rail, the device will be tightened on the rail base when the body of the anchor is swung horizontally toward 15 a position perpendicular to the length of the rail, which hereafter, for convenience, I have termed the "transverse position".

By my construction I am enabled to provide an anchor comprising nothing beyond 20 a bar of only slightly greater length than the width of the rail, for which the anchor is designed, provided with a single jaw at each end, which jaws may be applied in gripping position upon a rail base, with one end of the bar, in the operative position of the anchor, closer to a tie or other fixed abutment than is the other end. Preferably the one end is applied in contact with the tie or other fixed abutment. Following this 25 initial application of the device, pressure is applied tending to swing the body of the anchor toward the directly transverse position on the rail, whereby the anchor is moved into its operative tightened engagement on the rail, such final tightening being effected before the body of the bar passes the directly transverse position.

Preferably also this device is so constructed that when once applied to the rail it can 30 never under service conditions become so loosened as to drop from the rail and if properly proportioned for the particular rail to which it is applied, will at all times have a resilient grip on the rail, which resilient grip is progressively tightened by the forces which tend to cause creeping of the rail.

A further object of my invention is to provide a rail anchor of the flat metal type which is stamped out of sheet steel and arranged edgewise to the base of the rail, so constructed that the body of the anchor may be given any desirable section as to breadth and thickness to successfully resist forces tending to cause breakage without thereby interfering with the capacity of the device for being readily applied to or removed from the rail, confining the operative resiliency, if desired, entirely or almost so to the jaws or to the parts connecting the jaws with the body of the anchor.

It is thus the general purpose of my invention to provide a rail anchor characterized by simplicity of structure, readiness of application, strength, efficiency, economy of manufacture, durability, and economy of material, and having various other advantages as are hereafter pointed out.

In the more specific embodiment of my invention, it is one of my objects to provide 50 an anchor comprising a jaw at each end so arranged with reference to each other and to the body of the anchor that as the anchor after application is swung from a position diagonal toward a position transverse on the rail, the jaws will be operatively tightened upon the sloping upper faces of the base flanges of the rail, before the body of the bar passes such directly transverse position.

It is another object of my invention to provide a construction provided with jaws overhanging the base flange of the rail and comprising also one or more bearings, preferably in the form of shoulders, which will 55 tighten against the side edges of the base flanges when the bar is swung toward the directly transverse position.

Another object of my invention is to provide an anchor having a jaw at each end thereof, said jaws being so proportioned and positioned with relation to the body of the anchor that one of said jaws must and may be sprung outwardly to enable the device to be initially applied to the rail base from beneath the rail with the jaws overlying the base flange of the rail and with the body of the anchor diagonal to the length of the rail, the position of said jaws with relation

to each other and to the body of the anchor being such that as the body of the anchor is swung from its position of initial application toward a position transverse of the rail, 5 one of the jaws will offer greater resistance than the other to being forced inwardly and upwardly upon the rail flange so that the jaw which was initially sprung over the rail base, as above noted, will thereafter upon 10 the movement of the body of the anchor toward the directly transverse position be more readily drawn and moved upwardly and inwardly over the upper tapered surface of the rail base than will the opposite 15 jaw. This enables me to so construct my device that the jaw which must be sprung outwardly to permit of the initial application to the rail base, need only slightly overlap the rail base upon completion of such 20 initial application, but upon the swinging of the device toward the directly transverse position will be drawn, as well as swung, upwardly and inwardly over the rail base.

Another object of my invention is to provide such a device having resilient jaws extending inwardly at different angles with relation to the body of the device and arranged to overlap and resiliently grip the rail base when applied thereto, one or both 30 of such jaws being provided with bearings for initially or ultimately engaging the edges of the rail base, such bearings being offset from the body of the anchor so that when the device is swung toward the transverse 35 position the rail will be gripped horizontally between the said bearings and on the upper surfaces of the rail base by said jaws.

It is also among the objects of my invention to improve devices of this character in sundry details hereinafter pointed out.

The preferred means by which I have accomplished my several objects are illustrated in the accompanying drawings and are hereinafter specifically described.

45 That which I believe to be new and desire to cover by Letters Patent is set forth in the claims.

Fig. 1 is a face view of the blank from 50 which one form of my improved anchor is made.

Fig. 2 is a top plan view of the anchor in preliminary position on a rail, which is partly broken away for clearness of illustration.

55 Fig. 3 is a view similar to Fig. 2, but showing the anchor in its final operative applied position.

Fig. 3^a is a detail showing how the device is initially applied to the rail.

60 Fig. 3^b is a detail showing a "dog eared" corner on one of the jaws serving the same purpose as a taper to provide a cam surface engagement with the edge of the rail flange to spring the jaw outwardly upon its initial application to the rail base.

Fig. 4 is a face view of a modified form of blank.

Fig. 5 is a top plan view of the anchor formed from the blank of Fig. 4 and applied in its final operative position on a rail, with 70 the head of the rail broken away, as in Figs. 2 and 3.

Fig. 6 is a view similar to Fig. 3, but showing an anchor of lighter material and showing the body of the device twisted by 75 its application to the rail.

Fig. 7 is a face view of a third form of blank, and

Figs. 8 and 9 show the anchor formed from the blank of Fig. 7, as applied respectively in the initial position and the final operative position on a rail.

Referring to Figs. 1, 2 and 3:

10 indicates a bar comprising the body of my improved anchor. This will preferably 85 be cut from a heavy sheet of steel which for that reason will have more or less resiliency.

While some of the advantages of my invention may be attained even though there 90 be a resilient twisting or torsion of the bar, during application or while in service, I consider that best results are attained when the body of the bar is for all practical purposes rigid, confining the resilient feature to the 95 jaws, or to the jaws and the parts of the device which connect the jaws with the body of the anchor. My invention, therefore, broadly contemplates the described structure, whether comprising an appreciably 100 resilient body with jaws which conceivably may or may not be resilient, or a substantially rigid body with resilient jaws.

So far as certain features of my invention are concerned, it is not essential that 105 there be any resiliency either in the body or in the jaws, nor is it essential that the device be formed in one piece.

In the preferred form, however, the entire device is formed of one piece of heavy 110 sheet steel so proportioned and of such gauge that the body is substantially rigid and the jaws have a resilient relation to the body of the anchor and to the rail.

In such embodiment of my invention, the 115 body 10 is provided at one end with an inwardly projecting jaw 11 formed integrally therewith and bent out of the vertical plane of the body so as to project inwardly at an angle from one face of the body. The 120 stamping and bending of the jaw to its operating position may be effected by a single stamping and shaping operation.

As is shown in Fig. 1, in which the blank 125 is illustrated as being stamped with the jaws in alignment with the body, the vertical distance between the lower bearing edge of the jaw 11 and the upper bearing edge of the body is preferably less than the corresponding thickness of the flange of the rail 130

12, for which the anchor is designed. It will be clear, however, that this is another feature which, while desirable, is not essential. An outline of a cross section of the rail is shown in dotted lines in Fig. 1.

The body 10 is also provided at its end opposite to the jaw 11 with an inwardly projecting jaw 13, which is also shown in this embodiment as formed integrally with 10 the body and bent out of the vertical plane of the body so as to project inwardly from that face of the body which is opposite to the one from which the jaw 11 projects.

In the form illustrated in Fig. 2, it will 15 be noted that the jaws 11 and 13 are bent at different angles to the body 10 so that jaw 13 will overlap the rail base upon initial application to a much less extent than the jaw 11. It will also be noted that the bearing 20 edge of the jaw 13 as there illustrated is positioned slightly farther from the body 10 than is that of the jaw 11. Also that the jaw 13 is somewhat longer than the jaw 11.

These are all details of the preferred 25 form, but are not essential. Preferably also, as shown, but not necessarily, there is a greater lateral clearance between the body of the anchor 10 and the jaw 13, than there is between the body portion 10 and the jaw 30 11, for reasons which will be later explained.

With this preferred embodiment of my 35 invention, the device is applied to the rail by placing the body 10 across the bottom face of the rail in diagonal position with respect thereto. It will be observed that with the jaws arranged and proportioned as shown, the distance from the shoulder or bearing at the outer end of one jaw to 40 the inner end of the other jaw of the device is less than the width of the rail base.

In applying the anchor to a rail, the jaw 11 is hooked over one flange of the rail. This can be readily done by slightly tilting the 45 body of the anchor. The body of the anchor is then moved toward a vertical position, thereby putting the jaw 11 under a slightly spreading strain, due to the fact that the clearance between the jaw 11 and the body of the anchor 10 is less than the corresponding thickness of the rail base. This swinging of the device in a vertical plane will bring the tapered upper edge of the jaw 13 in contact with the lower 50 surface of the base flange of the rail adjacent its opposite edge. To enable the jaw 13 to clear the rail base and permit the completion of the initial application, the jaw 13 is sprung outwardly and upwardly 55 by a suitable tool until it clears the edge of the rail base whereupon it will snap over into engagement with the upper face of the rail base slightly overlapping the same as shown in Fig. 2.

60 To complete the application of the an-

chor, the end farthest away from the tie, and preferably with the other end resting against the tie or similar abutment, is then driven or otherwise forced toward a directly transverse position on the rail, that 70 is toward the tie.

The size, proportions and arrangements of the anchor and jaws are such that when the anchor is thus given a horizontal swinging movement the tendency is to cause the 75 jaws 11 and 13 to travel inwardly and upwardly over the sloping upper faces of the base flange of the rail, causing such jaws to progressively tighten upon the rail as the directly transverse position is ap- 80 preached.

Owing, however, to the difference in the 85 positions of the jaws 11 and 13, with relation to the body 10, the jaw 11 will not be as readily forced inwardly and up- 90 wardly over the sloping surface of the rail base 12, as will the jaw 13. Consequently under the horizontal swinging movement of the body, the jaw 13 will move more rapidly inward toward the web of the rail 95 than will the jaw 11. In fact, the tendency will be to draw the whole body of the anchor toward the left, as shown in Fig. 1, until a balance of forces is reached, thereby insuring an increasing contact be- 100 tween the jaw 13 and the top of the rail base.

By this construction I am enabled to 105 provide a device which can be readily sprung onto the rail by springing one of the jaws out of its normal position, thereby insuring that the device can never be dropped from the rail. At the same time I do this without sacrificing any ultimate effective engagement between the jaws and the rail base.

With the device as thus constructed, it 110 will be observed that the effective engagement of the device with the rail base depends upon the grip of the jaws against the upper surface of the rail base and the grip of the body against the bottom of the rail base. As so constructed, the anchor is designed to be made of material of such weight and strength with relation to the 115 service for which it is intended, that it will attain an operative working grip of the desired character before it reaches the transverse position which is designed to be the extreme limit of the swinging movement.

If the anchor is made of lighter material, the tightening of the anchor upon the rail may involve a twisting or torsion of the body or bar 10 of the device, as is 120 shown in Fig. 6. While there may or may not be a limited torsional twist of this character, even in the device when constructed as shown in Figs. 1, 2 and 3, according to the weight and character of 125 130

material used, such twisting, if any, will be slight, is not essential so far as my broad invention is concerned, and in my judgment is not desirable. With sufficiently heavy material, the resilient action will be substantially or wholly confined to the jaws even when the whole device is stamped out of a sheet of resilient material, such as sheet steel.

- 10 In Figs. 4 and 5, the construction is similar to that described above. In this construction, however, the cut between the jaw 11 and the bar 10 is made substantially square so as to provide a more pronounced shoulder 15 for engagement with the side edge of the flange than is provided in the construction of said Figs. 1, 2 and 3. This shoulder may be so arranged as either to engage the rail edge initially, or only after 15 the device has been swung from its initial position. In Figures 1, 2 and 3 the cut is made upon a curved line to avoid possible checking by reason of which the metal might tend to crack, the desired "shoulder" 20 being provided by curved end portions of the face defining the cut.

In the construction of Figs. 4 and 5, the jaw 13 is also provided with a shoulder. As will be appreciated from an inspection of Fig. 4, it is designed that the shoulder 16 shall be of sufficient scope vertically to provide an effective bearing against the edge of the base flange, a portion of the metal of the bar 10 being removed if deemed advisable, 35 as at 16^a in Fig. 4, for facilitating the stamping operation.

The anchor of Figs. 4 and 5 is applied to the rail in the same manner as is above described in connection with Figs. 1, 2 and 3. 40 The size and proportions of this modified form of anchor are such that when the anchor is given the swinging movement toward the position directly transverse of the rail, not only do the jaws 11 and 13 tighten 45 upon the upper faces of the flanges, but when shoulder 16 engages the edge of the base, jaw 11 must move upwardly and inwardly over the rail base until shoulder 15 engages and grips the opposite edge of the base, which will be either before or after a 50 perceptible swinging movement according to the distance between shoulders 15 and 16, the arrangement being such that the tightening of the bearings or shoulders 15 and 16 55 on the edges of the base flange is effected before the bar or body 10 passes a directly transverse position.

If the bearing 16 is so located as not to initially contact with the rail edge, the horizontal swinging movement will force jaw 13 to ride upwardly and inwardly to a greater extent than jaw 11, until jaw 16 does so contact.

In the form of anchor shown in Figs. 7, 8 60 and 9, the construction is the same, except

that each of the jaws 11 and 13 is provided with a bearing or shoulder corresponding to the shoulder 16 of Fig. 5. These bearings in Figs. 7, 8 and 9 are indicated by the numerals 17 and 18, respectively. As 70 illustrated in Figs. 7, 8 and 9, these shoulders 17 and 18 preferably extend the full height of the side edges of the base flange of the rail and are located an effective distance away from the junction between body 10 75 and jaws 11 and 13, respectively.

In the construction thus shown, the shoulders 15 and 16 of Fig. 5 and the shoulders 17 and 18 of Fig. 9 are preferably spaced apart by a distance very slightly greater 80 than but substantially equal to the width of the rail. It follows, accordingly, that the horizontal swinging movement of the anchor on a rail is limited in both directions. As is shown in Fig. 8, the anchor is preferably applied in initial position upon the rail at about the limit of its swinging motion away from the directly transverse or perpendicular position. Upon the initial swinging movement of the anchor toward 85 such transverse position from its extreme diagonal position, as shown in Fig. 8, the shoulders 17 and 18 will first be moved slightly away from the side faces of the flanges, but the important feature is that 90 upon a continued movement toward the transverse position these shoulders will engage and be tightened against the opposite edges of the base flange before the bar passes the directly transverse position, perpendicular 95 to the length of the rail.

While I have shown the tie 14 in each instance in engagement with the end of the anchor adjacent to the longer jaw 13, it will be understood that the anchor may be reversed in position on the rail so that the tie 105 will engage the opposite end portion of the anchor and on the opposite face thereof. Thus, the anchor may be applied with either face next to the tie as may be desired, the 110 operation of the anchor being substantially the same in every respect in either event.

In each instance, the arrows show the direction in which the rail tends to creep.

So far as I am aware, I am the first in the 115 art to provide an anchor comprising merely a bar with a single jaw at each end, such bar being of only slightly greater length than the width of the rail for which the anchor is designed, adapted to be tightened upon the 120 rail by a horizontal swinging movement of the bar from an initial diagonal position toward a directly transverse position on the rail, the arrangement being such that the tightening into final operative position is 125 effected before the bar passes the directly transverse position, whereby the end portion of the bar or body nearest to the tie or other fixed abutment may be utilized for bearing 130 against such abutment without the necessity

for providing offset portions or extensions of any kind for such bearings. Inasmuch as this expedient enables me very greatly to simplify the construction, and very greatly 5 to reduce the weight in proportion to the strength of the grip, and thus very greatly to reduce the cost of production and the cost of shipment, and also to produce an adequately heavy anchor having a resilient 10 grip, I desire to claim this feature broadly.

Indeed, my claims should be interpreted to cover such a construction in which the anchor assumes the operative tightened condition upon the rail before the bar passes the 15 directly transverse position even though the proportions be such that under the heaviest traffic conditions the bar might pass very slightly the exactly transverse position on the rail, the essential feature being that the 20 anchor shall assume its normal operative gripping engagement before the bar passes such directly transverse position.

By an inspection of the several figures of the drawings, it will be seen that in each of 25 the several constructions the line joining a part of the anchor effectively engaging the rail at one side with the complementary part of the anchor so engaging the rail at the opposite side is at an angle with respect to the 30 bar 10 of the anchor. This is true both of the line joining the bearings of the anchor upon the upper faces of the flanges and also of the line joining the bearings at the edges of the flanges. By an inspection of the sev- 35 eral figures of the drawings in which the anchor is shown in its final operative position on the rail, it will be seen that in each instance the line of bearings as above defined has passed the directly transverse position 40 with respect to the rail before the bar has attained a directly transverse position, serving thus to prevent the bar from passing such directly transverse position.

Since the resilient yielding may be confined to the jaw members, I am enabled to make my anchor of heavier stock than is possible where torsion or bending of the body of the anchor is essential in applying and holding the anchor on the rail. Thus I am enabled to provide an effective anchor of sheet metal of such weight and strength as to successfully resist those forces which under service conditions cause extensive breakage 50 in anchors of other types.

By my construction, I am enabled to make 55 such heavy anchors from sheet metal which will be held on the rail at such an angle away from the face of the tie, that the well known "shackle action" can be availed of to 60 tighten the grip of the device upon the rail without having to provide separate abutments for that purpose, or having to provide additional metal to be bent to form such lateral abutment from the body of the 65 anchor.

With heavy anchors, such additional metal, and the bending of the same to provide an abutment, would add substantially to the material and labor cost.

By my invention, I provide an exceedingly 70 simple and strong device, which may be stamped in one piece and formed with a minimum of operations requiring a minimum of material and labor in manufacture, capable of being easily and quickly applied 75 to a rail and affording a maximum of efficiency.

The specific features as to springing the device to initial engagement on the rail, providing jaws of different lengths and arranged at different angles, and like matters of detail, are all valuable but not essential 80 so far as my broad invention is concerned.

Having described my invention, what I 85 claim is:

1. A one piece rail anchor consisting only of a substantially straight bar having one rail gripping jaw at each end, so formed that when applied to a rail with one end abutting a tie, the body of the device will 90 extend at an angle away from the tie.

2. A rail anchor comprising a bar having jaws at its ends and adapted to be applied at an angle to the length of a rail, with said jaws extending over the base flange of the 95 rail and at such an angle to the bar as to cause tightening of the jaws upon said flanges when the bar is moved towards a position perpendicular to the length of the rail.

3. A one-piece rail anchor consisting only of a substantially straight bar having one rail gripping jaw at each end, said jaws being bent from the plane of the bar at opposite faces thereof so as to extend away from the bar, one of said jaws being disposed at a comparatively great angle with respect to the bar so as readily to snap past the edge of the adjacent flange of the rail in the application of the anchor to a rail, and the other jaw being disposed at a comparatively smaller angle with respect to the bar for operative engagement with the upper face of the rail flange at a correspondingly greater distance from the edge thereof. 105

4. A rail anchor comprising a single piece of sheet metal having integral jaws at opposite ends thereof and bent laterally away from the body of the anchor, said jaws being bent at different angles to the body of the anchor and being so spaced from each other that the maximum space between the opposite faces of said jaws is less than the width of the rail base, whereby one of said jaws must be sprung laterally away from the body of the anchor to permit application of the device to the base of the rail of the dimensions for which such device is designed. 115

5. A rail anchor comprising a bar having jaws at its ends and adapted to be ap- 120 125 130

plied at an angle to the length of the rail with said jaws extending over the base flange of the rail and at such an angle to the base as to cause tightening of the jaws upon said flanges when the bar is moved toward a position perpendicular to the length of the rail.

6. A rail anchor comprising a bar having resilient jaws at its ends and adapted to be applied at an angle to the length of the rail, with said jaws extending over the base flange of the rail and at such an angle to the base as to cause tightening of the jaws upon said flanges when the bar is moved toward a position perpendicular to the length of the rail, the space between said jaws being such that one of said jaws must be sprung laterally from its normal position to permit application of the device to a rail base.

7. A rail anchor comprising a bar having jaws at its ends and adapted to be applied at an angle to the length of a rail, with said jaws extending over the base flange of the rail and at such an angle to the base as to cause tightening of the jaws upon said flange when the bar is moved toward a position perpendicular to the length of the rail, one of said jaws being provided with a vertical shoulder arranged to be brought into engagement with the edge of the rail base in applying the device to operative engagement with the rail.

8. A rail anchor comprising a bar having jaws at its ends and adapted to be applied at an angle to the length of a rail, with said jaws extending over the base flange of the rail and at such an angle to the base as to cause tightening of the jaws upon said flange when the bar is moved toward a position perpendicular to the length of the rail, each of said jaws being provided with a vertical shoulder whereby in swinging said device to operative engagement with the rail base, the opposite edges of the base flange will be gripped between said shoulders.

9. A rail anchor comprising a bar adapted to be applied obliquely across the underside of a rail and provided with jaws arranged so as to engage over the base flange of a rail with an increasing grip as said bar is swung toward a position perpendicular to the rail length.

10. A rail anchor comprising a bar provided with a single resilient jaw adjacent each end thereof, said bar adapted to be applied obliquely across the under side of a rail, all so arranged that said jaws will engage the base flange of the rail with an increasing grip as said bar is swung toward a position perpendicular to the rail length.

11. A rail anchor comprising a flat bar of resilient metal arranged with its flat side

substantially vertical adapted to be applied obliquely across the under side of a rail and provided with a single integral jaw at each end thereof arranged so as to engage over the base flange of a rail with an increasing grip as said bar is swung toward a position perpendicular to the rail length.

12. A rail anchor formed of a flat bar of resilient metal adapted to be applied diagonally across the bottom of a rail with its flat side substantially vertical, provided with a single jaw at each end thereof, adapted to take over the upper face of the base flange of a rail, the relation between one jaw and the bar being such that the jaw must be sprung from its normal position to apply it over the rail base, said jaws being bent to such an angle with relation to the bar and to each other that the grip of the jaws will be increased as the anchor is swung from its original applied position to one more nearly perpendicular to the length of the rail.

13. A rail anchor consisting of a bar of resilient sheet metal provided with only a single integral jaw at each end thereof, said jaws being separated from the body of the rail by a space adapted to receive the opposite edges of the base flange of a rail only upon springing said jaws from their normal position, said jaws being oppositely bent at such relation to the bar and to each other that the bar can be only applied to the rail base obliquely to the length of the rail, and said jaws will be progressively tightened upon the rail when the bar is moved toward a position perpendicular to the rail length.

14. A rail anchor comprising a bar adapted to be applied obliquely across the under side of a rail and provided with jaws arranged so as to engage over the base flanges of a rail with an increasing grip as said bar is swung toward a position perpendicular to the rail length and means on said device arranged to engage and grip the rail before said bar has been moved past a position perpendicular to the length of the rail.

15. A rail anchor comprising a bar having resilient jaws at its ends adapted to be applied at an angle to the length of a rail, with said jaws sprung from their normal position over the opposite base flanges of such rail and extending at such an angle to the length of such rail as to assume operative tightening engagement with said flanges when the bar is moved toward a position perpendicular to the length of the rail.

16. A rail anchor comprising a substantially straight bar having jaws thereon at its end portions adapted to engage the base flange of a rail, and adapted to be fitted over the base of a rail at an angle to the axis of the rail, said jaws adapted to assume opera-

tive tightening engagement with said flanges when the bar is moved toward a directly transverse position with respect to the rail.

17. A rail anchor comprising a bar provided with jaws projecting inwardly intermediately of the outturned end portions of the bar, such jaws being adapted to engage the base flange of a rail, and to be given operative tightened engagement with said flanges when the bar is moved from its applied position toward a directly transverse position with respect to the rail, and before the bar passes such directly transverse position.

18. A rail anchor cut from a single piece of sheet metal comprising a substantially straight bar having jaws projecting inwardly intermediately of the outturned end portions of the bar, such jaws being adapted to engage the flanges at the opposite sides of a rail and to be given operative tightened engagement with said flanges when the bar is moved towards a directly transverse position with respect to the rail and before the bar passes such directly transverse position.

19. A rail anchor comprising a bar and jaws thereon at its end portions adapted to engage the flanges at the opposite sides of a rail, the spacing of the jaws with respect to each other and with respect to the bar being such that the bar is adapted to be swung towards a transverse position on the rail for tightening thereon, and is adapted to assume the operative tightened position with respect to the rail before the bar passes a directly transverse position thereon.

20. A rail anchor comprising a bar and jaws thereon at its end portions adapted to engage the flanges at the opposite sides of a rail, the spacing and arrangement of the jaws with respect to each other and with respect to the bar being such that the bar is adapted to be swung toward a transverse position on the rail, serving to cause the jaws to travel upwardly and inwardly on the flanges, and that the anchor is adapted to assume the operative tightened condition before the bar passes the directly transverse position.

21. A rail anchor comprising a bar having a jaw at each end portion thereof, said jaws being adapted to engage the flanges at the opposite sides of a rail, a single bearing being provided at each side of the rail in operative contact with the edge of the flange at that side, said jaws being adapted to assume operative tightened engagement with the flanges when the bar is moved towards a directly transverse position with respect to the rail.

22. A rail anchor comprising a bar having a single jaw only at each end portion thereof, said jaws being adapted to engage the base flanges at the opposite sides of a rail,

and to assume operative tightened engagement with the flanges when the bar is moved from its initial applied position toward a transverse position with respect to the rail.

23. A rail anchor comprising a bar substantially straight throughout its length, and jaws on said bar at its end portions adapted to engage the flanges at the opposite sides of a rail, the spacing and arrangement of the jaws with respect to each other and with respect to the bar being such that the bar is adapted to be swung towards a transverse position on the rail, serving to cause the jaws to travel upwardly and inwardly on the flanges, and that the anchor is adapted to assume the operative tightened condition before the bar passes such directly transverse position.

24. A rail anchor comprising a bar having a single jaw only at each end portion thereof, said jaws being adapted to engage the flanges at the opposite sides of a rail, the spacing and arrangement of the jaws with respect to each other and with respect to the bar being such that the bar is adapted to be swung toward a directly transverse position on the rail, serving to cause the jaws to travel upwardly and inwardly on the upper faces of the flanges, and that the anchor is adapted to assume the operative tightened condition before the bar passes such directly transverse position.

25. A rail anchor comprising a bar provided with jaws adapted to engage the flanges at the opposite sides of the rail, and to tighten upon such flanges when the anchor is swung toward a directly transverse position on the rail, the arrangement being such that the line joining the bearings of the anchor on the rail at its opposite sides is at an angle with respect to the bar and such that in the swinging motion the said line of bearings passes the directly transverse position with respect to the rail before the bar attains a directly transverse position, and that the anchor assumes its final operative tightened condition on the rail before the bar passes such directly transverse position.

26. A rail anchor comprising a bar having end portions of greater width than the intermediate portions and jaws projecting from the inner edges of the end portions and adapted to engage the flanges at the opposite sides of the rail, said jaws being so positioned and proportioned that they assume operative tightened engagement with the flanges when the bar is moved towards a directly transverse position with respect to the rail.

27. A rail anchor comprising a bar cut from a sheet of metal and having integrally formed end portions of greater width than the intermediate portions, and jaws formed integrally with the end portions on the

- inner edges thereof, and bent out of the plane of the bar at opposite faces thereof, said jaws being adapted to engage the flanges at the opposite sides of a rail and 5 to assume operative tightened engagement with said flanges when the bar is moved toward a directly transverse position with respect to the rail.
28. A rail anchor comprising a bar and a plurality of jaws adapted to engage the flanges at the opposite sides of a rail, each of the jaws engaging one flange being adapted to tighten with respect to each of the jaws engaging the other flange when 10 the bar is moved toward a directly transverse position with respect to the rail.
29. A rail anchor comprising a bar having short outwardly directed end portions of greater width than the intermediate portions, and two jaws projecting from the inner edges of the end portions respectively, and adapted to engage the flanges at the opposite sides of a rail and to be tightened upon the rail when the bar is swung toward 15 a directly transverse position thereon, said two jaws being so relatively located that they are adapted by themselves by their grip upon the rail in cooperation with the bar to prevent the bar from swinging past 20 a directly transverse position.
30. A rail anchor comprising a bar, one end portion of which serves as a bearing against a fixed abutment, a jaw on said bar in spaced relation to said end portion for 25 engaging one flange of a rail, and a second jaw on said bar intermediate of the said bearing and the first named jaw for engaging the other flange of the rail, said jaws being adapted to assume operative tightened engagement with the flanges when 30 the bar is moved toward a directly transverse position with respect to the rail.
31. A rail anchor comprising a substantially straight bar cut from a sheet of metal, one end portion of the bar serving as the bearing against a fixed abutment, an inwardly projecting jaw on the opposite end portion of said bar adapted to engage one 35 flange of a rail, and a second inwardly projecting jaw formed on said bar intermediate of the said bearing and said first-named jaw adapted to engage the other flange of the rail, said jaws being adapted to assume operative tightened engagement 40 with the flanges when the bar is moved toward a directly transverse position with respect to the rail.
32. A rail anchor comprising a bar the length of which is only slightly greater than 45 the width of the rail for which the anchor is designed, and inwardly projecting jaws on the end portions of said bar adapted to engage the flanges at the opposite sides of the rail, the device comprising also a bearing at one end portion of the bar and 50 spaced from one face of the bar adapted to engage the side edge of one of the flanges, said bearing and the jaws at the opposite end portions being adapted to assume operative tightened engagement with the flanges 70 when the bar is moved toward a directly transverse position with respect to the rail.
33. A rail anchor comprising a bar, the length of which is only slightly greater than the width of the rail for which the anchor is designed, and inwardly projecting jaws on the end portions of said bar adapted to engage the flanges at the opposite sides of the rail, the device comprising also bearings at the end portions of the bar 75 and spaced from opposite faces of the bar adapted to engage the side edges of the flanges respectively, said bearings being adapted to assume operative tightened engagement with the flanges when the bar is moved toward a directly transverse position with respect to the rail.
34. A rail anchor comprising a bar the length of which is only slightly greater than the width of the rail for which the anchor is designed, and inwardly projecting jaws on the end portions of the bar and bent out of the plane of the bar at opposite faces thereof, said jaws being adapted to engage the flanges at the opposite sides of 80 the rail and to assume operative tightened engagement with the flanges when the bar is moved toward a directly transverse position with respect to the rail.
35. A rail anchor comprising a bar and 85 jaws adapted to engage the side edges and also the top faces of the flanges at the opposite sides of a rail when applied to the rail in diagonal position and given a twisting motion about a vertical axis toward a directly transverse position, the arrangement being such that upon such twisting movement from the initial applied position towards the transverse position the anchor may at first loosen with respect to the side 90 edges of the flanges and then tighten on said side edges, being adapted to assume the final operative tightened condition before the bar passes the directly transverse position.
36. A rail anchor comprising a bar and 95 jaws adapted to engage the side edges and also the top faces of the flanges at the opposite sides of a rail when applied to the rail in diagonal position, and given a twisting motion about a vertical axis toward a directly transverse position, the arrangement being such that the jaws tighten on the upper faces of the flanges 100 throughout the entire motion of the bar towards the directly transverse position, the anchor comprising also a vertical shoulder adapted to have direct contact with the side edge of one of the flanges, such shoulder 105 being given tightened engagement with the 110 bar.

edge of the flange before the bar passes the directly transverse position with respect to the rail.

37. A rail anchor comprising a bar and 5 jaws adapted to engage both the side edges and the top faces of the flanges at the opposite sides of a rail when applied to the rail in diagonal position, and given a twisting motion about a vertical axis toward a 10 directly transverse position, the arrangement being such that the jaws tighten on the upper faces of the flanges throughout the entire motion of the bar towards the directly transverse position, the anchor comprising 15 also vertical shoulders adapted to have direct contact with the side edges of the flanges, such shoulders being given operative tightened engagement with the edges of the flanges before the bar passes the directly 20 transverse position with respect to the rail.

38. A rail anchor comprising a bar and jaws thereon adapted to engage the flanges on the opposite sides of a rail, and comprising at one side a bearing adapted to have 25 direct contact with the edge of the flange, the arrangement being such that said bearing is tightened upon the edge of the flange by reason of the action of the jaw at the opposite side of the rail when the body is 30 swung towards the transverse position, the effective operative tightening being effected before the bar passes the directly transverse position.

39. A rail anchor comprising a bar, a jaw 35 at one end of the bar adapted to engage the base flange at one side of a rail, said bar having an end portion at the opposite end of greater width than that of the body portion between the ends, and a jaw formed integrally with said end portion and projecting 40 from the inner edge thereof in position to engage the base flange at that side of the rail, said jaw comprising a bearing positioned out of the plane of the bar and having 45 direct contact with the edge of the flange.

40. A rail anchor comprising a bar having end portions of greater width than that of the intermediate portion, and jaws formed 50 integrally with said end portions respectively, and projecting from the inner edges thereof in position to engage the base flanges at the opposite sides of a rail, each of said jaws comprising a bearing positioned out 55 of the plane of the bar and having direct contact with the edge of the flange at that side of the rail.

41. A rail anchor comprising a bar and 60 jaws thereon adapted to engage the flanges at the opposite sides of a rail, said jaws comprising bearings positioned out of the plane of the bar and adapted to have direct contact with the side edges of the respective flanges.

65 42. A rail anchor comprising a bar and

jaws thereon adapted to engage the flanges at the opposite sides of a rail, said jaws comprising bearings positioned out of the plane of the bar and adapted to have direct contact with the side edges of the respective flanges, the arrangement being such that said bearings are tightened upon the edges of the flanges when said bar is swung about a vertical axis towards a directly transverse position with respect to the rail. 75

43. A rail anchor comprising a bar and jaws thereon adapted to engage the flanges at the opposite sides of a rail, such jaws being bent out of the plane of the bar at opposite faces thereof, and said jaws comprising 80 bearings located out of the plane of the bar and adapted to have direct contact with the edges of the flanges.

44. A rail anchor comprising a bar and jaws thereon adapted to engage the flanges 85 at the opposite sides of the rail, such jaws being bent out of the plane of the bar at opposite faces thereof, and said jaws comprising bearings located out of the plane of the bar and adapted to have direct contact with 90 the edges of the flanges, the arrangement being such that said bearings are tightened against the edges of the flanges when the bar is swung toward a directly transverse position with respect to the rail. 95

45. A rail anchor comprising a bar and jaws thereon adapted to engage the flanges at the opposite sides of a rail, said jaws comprising depending bearings positioned out of the plane of the bar and adapted to 100 have direct contact with the side edges of the respective flanges, the arrangement being such that said bearings are tightened against the edges of the flanges and the jaws are tightened upon the upper faces of the flanges 105 when the bar is swung about a vertical axis toward a directly transverse position.

46. A rail anchor comprising a bar and jaws thereon adapted to engage the flanges at the opposite sides of a rail, one of said 110 jaws comprising a bearing positioned out of the plane of the bar and having direct contact with the edge of the flange, the arrangement being such that said bearing is tightened against the edge of the flange 115 when the bar is swung about a vertical axis toward a directly transverse position on the rail.

47. A rail anchor comprising a bar and jaws thereon adapted to engage the flanges 120 at the opposite sides of a rail, one of said jaws comprising a bearing positioned out of the plane of the bar and having direct contact with the edge of the flange, the arrangement being such that said bearing is tightened against the edge of the flange and the jaws are tightened upon the upper faces of the flanges when the bar is swung about a vertical axis toward a directly transverse 125 position on the rail. 130

48. A rail anchor comprising a bar having one end portion of greater width than the intermediate portion, a jaw projecting from the inner edge of said end portion, and a second jaw on the bar at its opposite end portion, said jaws being adapted to engage the flanges at the opposite sides of a rail, said first-named jaw being provided with a depending shoulder for engaging the side 10 edge of the adjacent flange.
49. A rail anchor comprising a bar having end portions of greater width than the intermediate portions, and jaws projecting from the inner edges of the end portions and 15 adapted to engage the flanges at the opposite sides of the rail, each of said jaws having formed thereon a depending shoulder in spaced relation to the body of the bar, said shoulders being adapted to engage the side 20 edges of the adjacent flanges.
50. A rail anchor comprising a bar having one end portion of greater width than the intermediate portion, a jaw projecting from the inner edge of said end portion, and 25 a second jaw on the bar at its opposite end portion, said jaws being adapted to engage the flanges at the opposite sides of a rail, said first-named jaw being provided with a shoulder formed thereon independently of 30 the bar for engaging the side edge of the adjacent flange, the arrangement being such that the shoulder is tightened against the flange when the bar is swung about a vertical axis towards a directly transverse position 35 on the rail.
51. A rail anchor comprising a bar having end portions of greater width than the intermediate portions, and jaws projecting from the inner edges of the end portions and 40 adapted to engage the flanges at the opposite sides of the rail, each of said jaws having formed thereon a shoulder in spaced relation to the body of the bar, said shoulders being adapted to engage the side edges of 45 the adjacent flanges, the arrangement being such that the shoulders are given a shackle grip on the side edges of the flanges when the bar is swung about the vertical axis towards a directly transverse position on the 50 rail.
52. A rail anchor comprising a bar and jaws thereon adapted to engage the flanges at the opposite sides of a rail, and comprising bearings having direct contact with the 55 side edges of the flanges, one of said bearings being located out of the plane of the bar, said bearings being normally spaced apart by a distance substantially equal to the width of the rail whereby such bearings are tightened upon the edges of the flanges 60 when the bar is swung about a vertical axis toward the directly transverse position on the rail.
53. A rail anchor comprising a bar and jaws thereon adapted to engage the flanges at the opposite sides of a rail, such jaws being bent out of the plane of the bar at opposite faces thereof, and said jaws comprising bearings located out of the plane of the bar 65 and adapted to have direct contact with the edges of the flanges, said bearings being normally spaced apart by a distance substantially equal to the width of the rail.
54. A rail anchor comprising a bar and jaws thereon adapted to engage the flanges at the opposite sides of a rail, such jaws being bent out of the plane of the bar at opposite faces thereof, and said jaws comprising bearings located out of the plane of the bar 70 and adapted to have direct contact with the edges of the flanges, said bearings being normally spaced apart by a distance so nearly equal to the width of the rail and the bearings being located at such distance from the 75 faces of the bar that when the bar is swung from its initial applied position directly toward a transverse position on the rail, such bearings are tightened against the side edges 80 of the flanges.
55. A rail anchor comprising a bar and jaws thereon adapted to engage the flanges at the opposite sides of a rail, one of said jaws being bent out of the plane of the bar and being provided with a bearing in the 85 form of a shoulder of a height not less than substantially equal to the thickness of the edge of the flange, such bearings being adapted to have direct contact with the edge 90 of the flange.
56. A rail anchor comprising a bar and inwardly projecting jaws thereon adapted to engage the flanges at the opposite sides of a rail, said jaws being bent out of the plane of the bar at opposite faces thereof 95 and being provided with bearings in the form of shoulders of a height not less than substantially equal to the thickness of the edge portions of the flanges, such bearings being adapted to have direct contact with 100 the edges of the flanges.

CHARLES F. YARDLEY.
